(57) **CLAIM**

The ornamental design for a pilates machine, as shown and described.

DESCRIPTION

FIG. 1 is a front, top perspective view of a pilates machine, showing my new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of detail "9" identified in FIG. 2; FIG. 10 is another front, top perspective view of the pilates machine, shown in an environment of use; and,

FIG. 11 is a rear, bottom perspective view thereof.

The evenly dashed broken lines are shown for the purpose of illustrating both parts of the pilates machine as well as environmental subject matter. The dash-dot-dash broken lines in FIGS. 2 and 9 depict the bounds of the enlarged views. None of the broken lines form part of the claimed design.
